F. G. Fischer,
ATTORNEY.

UNITED STATES PATENT OFFICE.

ORA B. GILBERT, OF PLEASANT HILL, OHIO.

WINDOW-SHADE HOLDER.

1,158,677.

Specification of Letters Patent.

Patented Nov. 2, 1915.

Application filed December 3, 1914. Serial No. 875,303.

To all whom it may concern:

Be it known that I, ORA B. GILBERT, a citizen of the United States, residing at Pleasant Hill, in the county of Miami and State of Ohio, have invented certain new and useful Improvements in Window-Shade Holders, of which the following is a specification.

My invention relates to improvements in window-shade fixtures, and one object is to provide an adjustable holder which may be lengthened or shortened to accommodate shade rollers of different lengths.

A further object is to provide means for balancing the holder and raising and lowering the same, so that when a window sash is lowered from the top for ventilation, the holder, with the shade may likewise be lowered and thus avoid obstructing the passage of air.

Other objects of the invention will herein-after appear, and in order that said invention may be fully understood, reference will now be made to the accompanying drawing, 25 in which:

Figure 1 is a front elevation of a part of a window provided with my invention. Fig. 2 is a side elevation of the invention. Fig. 3 is a rear elevation of the holder and its 30 supporting cord. Fig. 4 is a detail perspective view of the intermediate section of the holder. Figs. 5 and 6 are detail perspective views of the end sections of the holder. Fig. 7 is a cross section, enlarged, on line 35 VII—VII of Fig. 1. Fig. 8 is a broken inverted plan view of one end of the holder. Fig. 9 is a section on line IX—IX of Fig. 8.

A designates the window casing, B the window shade, and C the shade roller, which 40 may be of the Hartshorn or other type of roller.

1 designates the shade roller holder, constituting one of the important features of the invention. Said holder consists of an 45 intermediate section 2 and a pair of end sections 3, all of which are, preferably, made of sheet metal. The sections 2 and 3 are of rightangular form in cross section, to lend rigidity thereto, and also to protect the top 50 and front of the roller C and that portion of the shade rolled thereon, from dust. The top side of the holder, however, does not extend rearwardly sufficiently to contact and mar the window casing. The end sections 55 3 have longitudinal flanges 4 arranged parallel thereto and spaced a slight distance

therefrom to provide grooves 5, for the reception of the top and bottom margins of the intermediate section 2, upon which the end sections 3 are slidably-mounted, so that 60 the holder 1 may be lengthened or shortened to accommodate shade rollers of different lengths.

The outer terminals of the end sections 3 have end plates 6, bent at rightangles to 65 their front sides 7 and secured by overlapping lips 8, bent downward from the top sides 9 of said end sections 3. The end plates 6 are further secured to the top sides 9, by lugs 8^a, bent at rightangles to the upper sides of said end plates and extending into the ends of the adjacent grooves 5, where they are secured between the upper flanges 4 and the top sides 9, Figs. 8 and 9. One end plate 6 has a round hole 10, while 70 its companion has a rectangular hole 11 to receive the round and the rectangular stubs of the shade roller C. The end plates 6 also have bumpers 12 of leather, rubber, or other suitable material which extend beyond the 75 stubs of the roller C, to prevent the same from marring the adjacent sides of the window casing, when the holder is hung between said sides and close to the window sashes.

13 designates a cord for supporting the shade holder and raising and lowering the same. One end of said cord 13 is formed into a loop 14, which freely extends through holes 15 in the top of the intermediate section 2, so that the holder can be readily adjusted and maintained in a horizontal position and thus insure straight rolling up and unrolling of the shade, so that it will be held in proper relation to the window. By 95 having the loop 14 extend through holes 15 in the intermediate section 2 of the holder, the end sections 3 may be adjusted apart or toward each other to accommodate shade rollers of different lengths, without in any 100 way interfering with the loop 14. One end of the loop 14 is secured to the cord in any suitable manner, a clip 16 being shown for this purpose. The free end of the cord 13 runs over a clutch pulley 17, of ordinary 105 type secured to the upper portion of the window casing A.

With the foregoing arrangement the shade can be raised and lowered bodily with relation to the window casing A, so as not to 110 obstruct ventilation when the window is lowered from the top. The shade may also

be rolled up to admit light through all or any part of the window, or it may be unrolled to shut out all light when desired.

From the foregoing description, it is apparent that I have produced a simple, efficient and inexpensive holder free from screws, bolts and other extraneous fastening devices, and while I have shown and described the preferred form of my invention, 10 I reserve the right to make such changes as properly fall within the spirit and scope of the claim.

Having thus described my invention, what I claim and desire to secure by Letters Patent, is:

A shade holder composed of an intermediate member and end members all of L-shape in cross section, the end members having grooved guides which slidably receive

the ends of the intermediate member, said 20 end members having extensions disposed at right angles thereto to form end walls therefor, said end walls having lugs which extend in the guides, and the top walls of the end members having right angular end 25 lips which engage over the outer faces of the end walls whereby to hold the latter against movement and to hold the lugs in the guides, said end walls having shade roller engaging means, and means connect- 30 ed to the intermediate member to support the entire device.

In testimony whereof I affix my signature, in the presence of two witnesses.

ORA B. GILBERT.
